UNITED STATES PATENT OFFICE.

GEORGE K. GUINZBURG, OF NEW YORK, N. Y., ASSIGNOR TO I. B. KLEINERT RUBBER COMPANY, OF NEW YORK, N. Y., A CORPORATION OF NEW YORK.

GARMENT PROTECTOR.

Application filed August 8, 1922. Serial No. 580,405.

To all whom it may concern:

Be it known that I, GEORGE K. GUINZBURG, a citizen of the United States, and a resident of the city, county, and State of New York, have invented a certain new and useful Improvement in Garment Protectors, of which the following is a specification.

This invention relates to a garment protector or baby pants usually worn by infants or young children to protect the outer clothing, and the object of this invention is to provide a device of this character which may be worn comfortably at all times and which will be very effective in preventing the escape of moisture resulting in consequent damage to the child's outer clothing.

As these garments are preferably made of an impervious material they sometimes prove uncomfortable at certain warm seasons of the year unless suitable means are provided for their ventilation, and a further object of this invention therefore is to provide suitable ventilating means for a garment of this character, such ventilating means being preferably located in such a position in the garment that the possibility of leakage therethrough is greatly minimized.

A still further object of the invention is to provide a garment protector preferably made of sheet rubber or any other impervious material provided at opposite sides adjacent the waist openings with suitable ventilating openings, such openings being so formed that the possibility of the garment tearing at that point is avoided; and said openings being also formed that they are normally kept open to at all times permit the free entrance of air and thorough ventilation of the garment is provided.

I am aware that garment protectors made of an impervious material and provided with ventilating openings have been heretofore made but these have generally been so constructed that the openings have been held normally closed while the garment was worn and consequently the desired thorough ventilation of the garment was not procured. A further defect of these prior constructions was found in the manner in which the openings were completely surrounded by an integral portion of the body of the garment, and located so that those portions of the garment which surrounded the openings were normally held flat against the body of the wearer with the result that it was very difficult for

air to enter the garment to produce the desired thorough ventilation. As will be hereinafter set forth, my improved garment is designed to overcome the defects found in the present forms of garment, and to provide a garment protector which can be worn with comfort and safety at all times.

Reference is to be had to the accompanying drawing, forming a part hereof, in which—

Figure 1 is a front elevation of a garment protector made in accordance with my invention;

Figure 2 is a perspective view of that portion of the garment wherein one of the ventilating openings is located;

Figure 3 is a sectional view on the line 3—3 of Figure 2, looking in the direction of the arrows; and

Figure 4 is a sectional view on the line 4—4 of Figure 1, looking in the direction of the arrows.

Throughout the various views of the drawings, similar reference characters designate similar parts.

In the preferred embodiment of my invention, as disclosed in the accompanying drawing, 1 indicates the front panel of the body of the garment, and 2 indicates the back.

The front and back portions 1 and 2 of the body are united by side seams 3, which extend diagonally from the skirted leg openings 4 to the lower ends of the ventilating openings 5. These seams are preferably formed and constructed that a water-tight joint thereat is produced, such joint being shown in section at Figure 4. It will there be seen that the edges of the front and back portions of the garment are overlapped and disposed on each side of these overlapped portions of the body are reinforcing strips 7 which thus hold the overlapped portions of the body between them. The joint is completed by the parallel lines of stitching 8^a which extend through the strips 7 and through the overlapped portions of the body. This construction produces a seam which by reason of its "finished" construction on both sides of the garment, enables the garment to be reversible and if desired, worn with either side outermost.

The garment may be made in various shapes and sizes to suit varying requirements. I have herein described the garment as being

applicable for use as a garment protector for infants and children, but it will be understood that it may be used as a protective device for women, and may be formed with 5 legs or trouser portions as desired without departing from the spirit of my invention.

At 6 is shown the waist opening which is similar in all respects to the leg openings in that it is produced with a shirred marginal- 10 portion, and is also provided with a flat strip of an extremely resilient and elastic material secured over the inner face of the shirring. These strips are shown at 8 and are secured in position by the double lines 15 of stitching indicated at 9. This arrangement permits expansion of the garment at the waist and leg openings to enable it to be placed on or removed from the wearer, and forms the subject matter of prior patents 20 issued to me.

The ventilating openings, indicated at 5, 5, are preferably located on the lines of the side seams 3, 3, and extend downwardly from the waist opening 6 and terminate a 25 short distance below the same. When so located the openings are in a position where protection is not necessary and the possibility of leakage therethrough is extremely slight. To produce an opening which will 30 be so reinforced that tearing of the material of the body will not readily occur, I utilize a strip of tough and resilient material which I secure about the edge of the opening 5. Such strips are indicated at 10 and may be 35 preferably secured in place by any suitable means, either adhesive or otherwise, and in this instance I utilize stitching 11.

The material of the binding 10 is of such 40 "resilient stiffness" that it normally holds the opening 5 distended or fully open regardless of the movements of the body of the wearer. This is an extremely important function of this portion of the device. Furthermore the binding 10 provides a form of 45 ring or mouth which projects outwardly from the body of the wearer and permits the free entry of air.

The openings 5, 5 may be formed by cutting downwardly from the upper edge or 50 waist line of the garment and thence holding the upper portions of said openings, after the bindings 10 have been placed in position, in overlapped position so that when the waist opening strip 8 is sewed in position, its securing stitches 9 will extend through the overlapped portions of the body 55 above the openings 5 to form a continuous and closed waist opening.

The above described construction is ideal 60 for the purpose. It enables the openings 5 to be produced by straight stitching, ena-

bling the garments to be turned out with accuracy and speed; it avoids the cutting out of portions of the body to produce the ventilating openings and consequent waste of material, and finally produces ventilating openings which are extremely effective and enable the garment to be comfortably worn under all conditions of use. 65

Having described one embodiment of my 70 invention it is obvious that the same is not to be restricted thereto, but is broad enough to cover all structures coming within the scope of the annexed claims. 75

What I claim is:-

1. An article of the class described comprising a garment having expansible waist and leg openings, said garment having ventilating openings extending downward from the waist opening and having means normally holding said openings in open position, with portions of said garment above the ventilating openings overlapped and permanently secured at the waist line in such overlapped position. 80 85

2. A garment of impervious material having a ventilating opening, the edge of the material surrounding said opening being covered by a binding of expansible material of tubular formation and of sufficient 90 resiliency to retain said opening in a distended or open position, with portions of the garment at the waist line and above the opening being overlapped and permanently 95 secured together in such overlapped relationship. 100

3. A garment of expansible impervious material having a pair of ventilating openings, each of said openings beginning at the 105 waist line of the garment and extending downward below the same, a tubular and elastic binding secured on the edge of the material surrounding the openings, said binding being of sufficient resiliency to hold said openings normally open or distended, with portions of the garment above the 110 openings overlapped and permanently secured in such overlapped position. 115

4. An article of the class described comprising a garment having a pair of ventilating openings, each of said openings beginning at the waist line of the garment and extending below the same, said garment being shirred adjacent the waist band and having a flat expansible band secured over the shirring, with portions of the garment above the ventilating openings being overlapped and held in such overlapped position by the securing means for the band. 120

Signed at the city, county and State of New York, this 28th day of July, 1922.

GEORGE K. GUINZBURG.
